Primary Examiner — Brett Miller*(74) Attorney, Agent, or Firm* — Pizarro Allen PC(57) **CLAIM**

The ornamental design for a vent cap, as shown and described.

DESCRIPTION

FIG. 1 is a front perspective view of a vent cap showing our new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof; and,

FIG. 9 is an environmental view of a container with the vent cap according to the claimed design.

The features shown in broken lines are for illustrative purposes only and form no part of the claimed design.

1 Claim, 7 Drawing Sheets(56)
